Primary Examiner — Elizabeth J Oswecki(74) *Attorney, Agent, or Firm* — Ryan Kromholz & Manion, S.C.(57) **CLAIM**

The ornamental design for a face mask, as shown and described.

DESCRIPTION

FIG. 1 is an exploded front view of a face mask showing my new design, the exploded rear view being identical;
FIG. 2 is another exploded perspective view thereof, shown in a used condition with the mouth and nose cover removed;
FIG. 3 is a perspective view thereof, shown in a used condition with the mouth and nose cover attached;
FIG. 4 is a left side elevation view thereof, shown in an unused condition;
FIG. 5 is a right side elevation view thereof;
FIG. 6 is a front elevation view thereof;
FIG. 7 is a rear elevation view thereof; and,
FIG. 8 is a top plan view thereof.
The broken lines shown in the drawings form no part of the claimed design.

1 Claim, 3 Drawing Sheets(56)
